UNITED STATES PATENT OFFICE.

ALLEN P. HARLAND, OF TUPELO, MISSISSIPPI.

ATTACHMENT FOR PRINTING-PRESSES.

No. 914,269.

Specification of Letters Patent.

Patented March 2, 1909.

Application filed April 6, 1903. Serial No. 425,422.

To all whom it may concern:

Be it known that I, ALLEN P. HARLAND, a citizen of the United States, residing at Tupelo, in the county of Lee and State of Mississippi, have invented a new and useful Attachment for Printing-Presses, of which the following is a specification.

This invention has reference to improvements in attachments for printing presses, whether of the cylinder and platen or web type, and the object of the invention is to convert such printing presses into multi-color printing presses.

In accordance with the present invention there are provided inking units which are removable and interchangeable, while at the same time provision is made for positively driving the inking rollers so that there may be no slipping. Furthermore, in accordance with the present invention provision is made whereby colors may be printed as closely together as desired, or may even be made to overlap and blend.

In the practical embodiment of the present invention there is used a single supplemental cylinder as wide as the surface to be printed, and as many inking units are employed as may be necessary for the number and location of colors desired. Furthermore, there is no danger of uneven printing because of the spring of the shaft carrying several supplemental cylinders, as might be the case were a number of separate supplemental cylinders used.

In accordance with the present invention there is provided a supplemental imprinting cylinder receiving motion from the main printing press, and geared to the shaft carrying the supplemental cylinder are other shafts, also thereby being positively driven. These last-named shafts each carry inking rollers which may be adjusted longitudinally upon said shaft, but are keyed thereto for positive rotation. In conjunction with the said inking rollers are inking units which may be removed at will and are interchangeably used in connection with any one of the inking rollers. Each inking unit comprises a suitable reservoir in which there dips a positively driven transfer roller for the ink and suitable other transfer rollers are provided for delivering the ink to the imprinting surface on the supplemental cylinder. Each inking unit includes, also, a means for imparting to one of the transfer rollers not only a

movement of rotation but a movement in the line of the axis of said roller, so that the ink is properly spread when fed to the rollers transferring the ink directly to the imprinting presses.

The invention will be best understood from a consideration of the following detail description taken in connection with the accompanying drawings forming a part of the specification, in which drawings,

Figure 1 is a plan view of a number of inking units in operative relation one to the other and also showing some of the coacting parts. Fig. 2 is an end view of the structure shown in Fig. 1 and also showing the portion of the supplemental cylinder. Fig. 3 is a section on the line A—B of Fig. 1. Fig. 4 is a longitudinal section of one of the inking units on the line C—D of Fig. 1. Fig. 5 is a plan view of two juxtaposed inking units, with some parts shown in section and some parts omitted. Fig. 6 is a sectional view, on a small scale, to show the manner of avoiding interference between the paper latches, on the main cylinder, and the supplemental cylinder.

Before entering into a detail description of the present invention it may be well to state that the invention relates to an attachment for multicolor printing, which is as well adapted to the cylinder and platen press as to a web press and may be used in connection with either type of press.

In Fig. 6 there is shown the cylinder 1, of a cylinder and platen press, and in operative relation to this cylinder is shown another cylinder 2 which constitutes the supplemental cylinder of the present invention. As shown in Fig. 6 and also in Fig. 2, it will be seen that the supplemental cylinder 2 is mounted upon a shaft 3, which, as shown in Fig. 2, has suitable bearings 4 in the framework of the press. In the present invention the cylinder 2 is as wide as the surfaces to be imprinted, whether said surface be in the form of sheets of paper or of a continuous web.

Mounted in suitable bearings 5 attached to the main frame of the press are shafts 6 and 7. The shaft 3 carries a gear wheel 8 which is in mesh with pinions 9 and 10 on the shafts 6 and 7, respectively, so that when the shaft 3 is driven the two shafts 6 and 7 are driven likewise but at a higher rate of speed.

2
Mounted upon each shaft 6 and 7 is a suitable number of inking rollers 11 each composed of a central hub or sleeve 12 of metal keyed to the shafts 6 and 7, and an outer surface 13 of composition such as is usually employed in connection with inking rollers of printing presses. The keys by means of which the inking rollers 11 are caused to participate in the rotative movement of the shafts 6 and 7, are in the form of splines 14 extending longitudinally of the shafts through the greater portion of the length of the latter, so that the rollers 11 may be adjusted upon the shafts to any desired point thereon and are there held by set screws 15 in any desired position of adjustment.

The inking rollers 11 constitute each a part of an inking unit, but not the removable interchangeable part. The last-named 20 part of the inking unit is composed of a suitable frame and ink reservoir, transfer rollers and another inking roller coacting with the first-named roller. The frame of the inking unit consists of two side plates 16 and 17 secured together in spaced relation parallel one to the other by suitable bolts 18 and another bolt 19, to which reference will presently be made.

30 Mounted in slots 20 in the side plates 16 and 17 of the frame of the inking unit is a shaft 21 of a composition inking roller 22, the latter being so located as to be in operative relation to the printing surface on the cylinder 2 when the inking unit is in operative relation to the cylinder 2. The bolt 19 between the two plates 16 and 17 is made square and receives a hook 23, the square bolt serving to hold the hook in any suitable position of adjustment. The hook 23 is located 40 preferably midway between the two plates 16 and 17, but it may be located nearer one plate than the other, if so desired.

At the end of the frame carrying the hook 23 there is mounted a metal roller 24 in operative relation to the reservoir 25 for ink. This ink reservoir 25 has an adjustable bottom 26 extending thereacross and the adjustment of this bottom 26 is effected by stop-screws 27 extending through the main 50 bottom of the ink reservoir or by any other suitable means. The adjustable bottom 26 besides serving to maintain the ink in the corresponding end of the reservoir, also serves as a scraper in connection with the roller 24.

55 Pivottally connected to the side plate 16 is a lever 27, and also pivotally connected to the side plate 17 is a link 28. The lever 27 and link 28 are connected at their free ends by a yoke 29, and the link and lever coact 60 to support the journal 30 of a transfer roller 31 which may be made of composition like the inking rollers 13 and 22. Mounted in slot bearings 32 in the frame sides 16 and 17 are journals 33 of the roller 34 made of metal, 65 and in contact with the inking rollers 13 and

22. The shaft 30 of the roller 31 projects through the lever 27 and there carries a grooved hub 35. The shaft or journal 33 projects through the side plate 16 and there carries a smaller hub 36, also grooved like the hub 35.

One journal 37 of the roller 24 projects through the plate 16 and there carries a disk 38, on diametrically opposite points of which are formed teeth or tappets 39. The disk 38 is also formed on opposite faces at diametrically opposite points with cam projections 40. Mounted in pivotal bearings 41 on the plate 16 is a lever 42 having one end provided with a pin 43 entering the groove in the hub 36, and on the opposite side of the pivot 41 this lever is provided with another pin 44 entering the groove in the hub 35. Beyond the pin 44 the lever 42 is formed into a fork 46 straddling the disk 38 and having the end of the fork in operative relation to the cam members 40. The roller 24 has its other journal 47 projecting through the plate 17 and there carries a worm wheel 48 in engagement with a worm 49 on a shaft 50 90 having journal bearings on the plate, and at the other end provided with the bevel pinion 51 in engagement with a bevel gear 52 on the corresponding end of the hub 12 of the roller 11. The hub 12 back of the gear 52 95 is formed with a circumferential groove 53, and on the other end with an extension 54.

At the end remote from the hook 23, each plate 16 and 17 is cut out to straddle the hub 12 in the groove 53 and extension 54, respectively. Fast to each plate 16 and 17 by a link 55 is a latch member 56 also cut out to partly encircle the hub 12 in the groove 53 or extension 54, as the case may be. A hook 57 pivotally secured to one of the bolts 100 18 is provided for fastening the latch member 56 by means of a pin 58 at the corresponding end of the latch member over which the hook 57 engages.

The supplemental cylinder 2 is in operative relation to another cylinder 59 which may represent either the cylinder of a cylinder and platen press or a corresponding cylinder of a web press.

Now, let it be supposed that it is desirable 115 to imprint in colors upon the page of a newspaper in spaces left for the purpose. The proper electrotypes are fastened upon the cylinder 2 in position to register with the blank spaces on the imprinted paper. Adjacent to the cylinder 2 and parallel therewith is a rod 60 suitably supported from the framework of the machine. This rod receives the hook 23 of the inking unit, while the latch end of the unit is engaged about the hub 12 of the corresponding inking rollers 11. The inking rollers 11 are brought into register with the part of the paper to be imprinted in colors, and then the inking units are hung upon the rod 60 and latched to the corre- 130

sponding inking rollers 11. Ink of the desired color is placed in the ink reservoir 25 and different colors may be placed in the several different reservoirs. If, now, the printing of the paper be assumed to be progressing the operation of the inking unit is as follows: The shafts 6 and 7 are positively driven and the rollers 11 participate in this movement. However, only those inking rollers 11 which receive ink from an inking unit cause the imprinting surface on the roller or cylinder 2 to imprint on the paper. The positive rotation of the shafts 6 and 7 impart constant movement to the rollers 24 through the shaft 50 and the worm gears 49 and 48. The lever 27 is provided with an angle arm 61 terminating in a roller 62 in the path of the teeth or tappet 39. When the roller 24 is set in rotation, the teeth 39 enter under the roller 62 and cause the lever 27 to rock on its pivot to bring the roller 31 into contact with the roller 24, and the roller 31 thereby receives a charge of ink. When the tooth 39 has passed from under the roller 62 the roller 31 returns into engagement with the roller 34, and the latter receives the ink carried by the roller 31. The lever 42 is in the meantime being rocked about its pivot by the engagement of the cam 40 with the fork end 46 of said lever 42, and this lever imparts to the rollers 31 and 34 a reciprocatory movement in the direction of the axis of these rollers. The ink is thereby evenly spread upon the rollers 13 and 22 and by the latter is transferred to the imprinting surface upon the cylinder 2, to be thereby in turn transferred to the spaces left in the main imprint upon the paper.

If it be desired to print the same matter in different colors at different times, then it is only necessary to unlatch the unit containing the color not wanted and to replace it with another inking unit having the color desired. Under such circumstances, it is only necessary to clean the inking roller 13 and the electrotype from which the impression is made.

Suppose it be desirable to print the same matter in two colors, then two inking units may be made to overlap, as shown at the right hand of Fig. 1, and one inking unit may carry one color and the other inking unit may carry the other color, and both deposit ink upon the same imprinting surface. It is also possible to make the colors actually overlap and thereby blend to any desired extent.

Ordinarily, the hooks 23 are arranged central to the inking unit, but they may be arranged a little to one side of the center so that two inking units on opposite sides of the rod 60 may be brought into exact alinement, and in such case two different colors may be made to blend entirely over the inked imprinting surface and thereby produce another color caused by the blending of the two colors supplied by the unit.

It will be observed that the only adjust-

ment or register needed is provided for by the inking rollers 11, which may be readily adjusted into register with the imprinting surfaces. The removable portion of the units are freely interchangeable one with the other and the inking rollers 11 determine the registering of the removable part of the inking unit with the matter to be inked.

It sometimes happens when the electrotype are thin that the supplemental cylinder 75 will engage the paper latches indicated at 63 on the main cylinder 1. To avoid this the electrotype may be cut out, as indicated at 64, Fig. 6, and may also be cut out as indicated at 65 for the spaces between pages.

What is claimed is:

1. In a multi-color attachment for printing presses, an imprinting cylinder and inking units each comprising a registering element adjustable parallel with the axis of the imprinting cylinder, and an interchangeable element adapted to be connected to and register with the registering element irrespective of the adjustment of the latter with relation to the imprinting cylinder.

2. In a multi-color attachment for printing presses, an inking unit having a registering element adjustable parallel with the axis of the imprinting surface, and an interchangeable element acting with the registering element and comprising an ink reservoir and all the ink transfer rollers except the registering element, said interchangeable element being removable as a whole from operative relation to the registering element 100 and capable of being placed into operative relation with other registering elements.

3. In a multi-color attachment for printing presses, a support, inking units carried thereby on opposite sides of the said support 105 and adjustable into any position of staggered relation.

4. In a printing press, an inking unit composed of a single inking roller adjustable across the surface of the imprinting surface, 110 and a removable element composed of a suitable frame, inking rollers therein, an ink reservoir and ink transfer rollers between the ink reservoir and the inking rollers.

5. In a multi-color attachment for printing presses, a printing cylinder, a support longitudinal thereto, and inking units each composed of a removable and interchangeable member carried at one end by the support, and provided with an ink reservoir and ink transfer rollers, and another member independent of the removable and interchangeable member and consisting of an inking roller and serving as a support for the other end of the removable member.

6. In a multi-color attachment for printing presses, a printing cylinder, and an inking unit therefor composed of an inking roller adjustable across the printing cylinder, and another inking roller and ink reservoir 130

in removable relation to the first inking roller.

7. A multi-color attachment for printing presses comprising a printing cylinder, a number of inking rollers adjustable across the said cylinder, and ink carrying and distributing members removable from and interchangeable with the adjustable inking rollers.

10 8. A multi-color attachment for printing presses comprising a single printing cylinder, two sets of individually adjustable inking rollers in operative relation to the printing cylinder on opposite sides of a median line, and removable and interchangeable inking elements in coactive relation with the inking rollers.

20 9. A removable inking attachment for printing presses comprising a frame having a hook at one end and a latch at the other end, an ink reservoir in the frame, an inking roller carried by the frame, and transfer rollers between the reservoir and the inking roller.

25 10. A removable inking attachment for printing presses, comprising a frame having a hook at one end and a latch at the other end, an inking roller carried by the frame, ink transfer rollers, and an ink reservoir provided with an adjustable bottom also constituting a scraper for the transfer rollers dipping into the reservoir.

30 11. A removable ink attachment for printing presses comprising a frame having a hook at one end and a latch at the other end, an ink reservoir in the frame, an inking roller carried by the frame, ink transfer rollers, an ink reservoir, and means for imparting reciprocatory movement to the ink transfer rollers other than the one dipping into the reservoir.

40 12. In a multi-color attachment for printing presses, an imprinting cylinder, and an inking unit comprising a registering element

adjustable parallel with the axis of the imprinting cylinder, and an interchangeable element adapted to be connected with a registering element, irrespective of the adjustment of the latter with relation to the imprinting cylinder, said interchangeable element including an ink transfer roller and positive connections between the power side of the press and both the registering element and the ink transfer roller.

45 13. In a printing press, a printing cylinder, shafts parallel thereto, inking rollers on and rotatable with each shaft and adjustable thereon in the direction of length of the shaft, said rollers each carrying a gear, and interchangeable inking elements removable from the inking rollers, said inking elements each comprising an ink reservoir, and ink transfer rollers and positive driving connections for the ink transfer rollers removably engaging the gear on the inking roller when the inking element is in position thereon.

50 14. In a printing press, a printing cylinder, shafts parallel thereto, inking rollers rotatable with the shafts and adjustable longitudinally thereon, said rollers carrying gears, and interchangeable inking elements removably mounted on the inking rollers, said inking elements comprising an ink reservoir, ink transfer rollers, positive driving connection between the ink roller and the transfer roller dipping in the ink reservoir, and means driven by the positively actuated ink transfer roller for reciprocating other transfer rollers.

55 In testimony that I claim the foregoing as my own, I have hereto affixed my signature 80 in the presence of two witnesses.

ALLEN P. HARLAND.
